United States Patent Office.

WILLIAM B. EMERY, OF ALBANY, NEW YORK.

Letters Patent No. 77,471, dated May 5, 1868.

IMPROVED MACHINE FOR THRESHING AND CLEANING GRAIN.

The Schedule referred to in these Letters Patent and making part of the same.

TO ALL WHOM IT MAY CONCERN:

Be it known that I, WILLIAM B. EMERY, of the city and county of Albany, in the State of New York, have invented a new and improved Mode of Constructing Machines for Threshing and Cleaning Grain; and I do hereby declare that the following is a full and exact description thereof.

The object of my invention is to combine, in a self-cleaning threshing-machine, (in which the straw-separator and the shoe are vibrated simultaneously in opposite directions,) an endless elevator, for the purpose of raising the straw and unseparated grain above the general level of the separator-floor, so that it may fall again upon the separator, and in so falling cause any dense masses of straw to become disintegrated more than they would be if allowed to pass off the separator without such action, thus more completely separating the grain.

I have heretofore made threshing-machines having this feature, but in those machines the straw-elevator was placed close to the discharging-side of the threshing-cylinder, so that the grain and straw issuing from the cylinder were received directly upon it, making it necessary to have the elevator lined with heavy painted canvas, to prevent the straw shooting through it, and becoming entangled in it, and to have the slats of the elevator made of very hard wood, and the whole construction of the elevator to be of the most substantial and expensive description, on account of the excessive wear and tear of the impinging grain and straw upon it.

Besides these objections to that mode, it may be added that repairs of the elevator were very difficult, if not impossible to be made in many places where the machines were used, from want of suitable materials, tools, and skill, while such repairs were very often needed on account of the excessive wear above mentioned.

In this machine I have moved the elevator D to a considerable distance from the threshing-cylinder A, so that a portion of the separator (which I term the apron, b b,) intervenes between it and the cylinder A, upon which apron the straw and grain are received before they reach the elevator, and upon which nearly all the force of the grain and straw is expended, so that the elevator need not be lined with canvas, but may be open between its slats, while the slats may be made of any soft and light wood, while the openings between the slats facilitate the separation of the grain, and the whole construction of the elevator is vastly simplified and cheapened. At the same time it is more durable, easily repaired by any one in any place, and, being lighter and more flexible, it is actuated with a less expenditure of power.

I have also attached to the bonnet, Y, or guide, (over the passage-way from the cylinder,) a crank, Y', or lever, having a handle on the outside of the machine, by which the bonnet may be elevated or depressed, so as to direct the current of straw and grain (issuing from the cylinder) upon the apron of the separator, at such an angle as may be required.

I have also elevated or turned upwards the lower edge of the apron, S, where it approaches the elevator D, so as to direct the straw, as it moves from the apron to and upon the elevator, upwards, thus facilitating its being carried up, and also preventing the straw becoming entangled between the slats, or falling through the openings into the interior of the elevator and clogging it.

The beater, N, may have teeth, (alternately protruding and withdrawing as it revolves,) or may be made in any usual manner. Its office is to assist the other parts of the machine by beating and agitating the straw (as it passes off the elevator) in making a complete separation of the grain from the straw.

The apron, b b, is covered with sheet iron, to prevent its wearing by the impinging grain and straw. It inclines downwards towards the elevator. There is an opening at t, in front of its elevated edge, s, through which the grain which is separated upon the apron may pass to the shoe and sieves without going through the elevator.

The lower edge of the sheet iron, covering the first section of the apron, extends at u over the head of the tossing-fork, protecting it from wear and preventing straw becoming entangled about it, or grain falling through the opening.

The upper edge of the sheet iron, covering the lower section of the apron, is turned up at v, under the projecting edge u of the upper section, to prevent grain falling off when thrown backwards by the vibrating of the separator.

The apron is sometimes perforated similarly to the after-part of the separator, $x x$, in which case a chaff and grain-board is inserted, as shown at T.

The chamber over the separator, enclosed by the side-boards J and the cover $k l$, extends in front of the concave to the point w, where it opens downwards towards the feeding-table z. Up through this opening, and along over the top of the concave A', a strong current of air is drawn, by the current of air, straw, and grain which is thrown by the cylinder, carrying with it all the dust which rises from the straw as it is fed to the cylinder, thus relieving the feeder of a most disagreeable and unhealthy annoyance.

The object of vibrating the separator and the shoe in opposite directions is to prevent the vibration of the whole machine itself. The force of each vibrating part, being counterbalanced by that of the other, causes the machine to stand perfectly at rest, relieving it from the destructive shocks which would result from the vibrating of so heavy a mass within it without such neutralizing of the thrusts.

I am aware that machines have been made having an elevator situated similar to mine, but in such machines the shoe and separator were so connected as to vibrate in unison or together.

The tossing-forks $b' b'$ are actuated by levers I I, which are made fast to the trunnions of the fork-heads, while the upper end is held loosely in a stationary loop, so that when the separator vibrates, carrying with it the forks, they are caused to vibrate in a vertical direction, thus lifting and shaking the straw as it passes over them.

The separator, as it swings outwards, also swings upwards, which combined motion causes the straw to move along towards and off its extremity without any other device.

Below is a recapitulation of the letters of reference on the drawing, which accompany and make a part of this specification.

A, threshing-cylinder.	A', concave, (over cylinder.)
B, separator.	C, shoe.
D, elevator.	$b b$, apron of separator.
$x x$, after-portion of separator.	$b' b'$, tossing-forks.
C', grain and chaff-board.	C'' C', sieves in shoe.
C'', grain-board.	E, grain-spout.
F, tailing-spout.	G C, suspenders of separator.
H H, suspenders of shoe.	I I, levers of tossing-forks.
J, side-boards.	M, curtain.
N, beater.	O, fan.
P, connecting-rod of separator.	Q, connecting-rod of shoe.
R, air-flue from fan.	S, raised edge of apron.
t, opening in front of edge S.	T, grain and chaff-board.
W, mouth of dust-flue.	Y, bonnet or guide.
Y', adjusting-lever to bonnet.	Z, feeding-table.

Having thus described my invention, what I claim as my invention, and desire to secure by Letters Patent, is—

1. Combining, with a self-cleaning threshing-machine, (in which the shoe and the separator vibrate in opposite directions,) an endless straw-elevator, having an apron between it and the threshing-cylinder, arranged substantially as and for the purpose specified.
2. Deflecting the edge S of the apron upwards, substantially as and for the purpose specified.
3. The beater N, in combination with the elevator D and apron $b b$, substantially as specified, (whether the shoe and the separator vibrate in opposite directions or in unison.)
4. The lever Y of the bonnet, whereby the bonnet may be adjusted from the outside of the machine, substantially as and for the purpose specified.
